UNITED STATES PATENT OFFICE.

GEORGE MOSES GODDARD, OF RUTLAND, VERMONT, ASSIGNOR OF ONE-HALF TO GEORGE C. THRALL, OF RUTLAND, VERMONT.

KEYBOARD TELEGRAPH-TRANSMITTER.

No. 850,364.

Specification of Letters Patent.

Patented April 16, 1907.

Application filed April 30, 1906. Serial No. 314,411.

To all whom it may concern:

Be it known that I, GEORGE MOSES GODDARD, a citizen of the United States, residing at Rutland, in the county of Rutland and State of Vermont, have invented a new and useful Improvement in Keyboard Telegraph-Transmitters, of which the following is a specification.

My invention relates to telegraph-transmitters of that form which does not require an expert telegrapher, but in which any one capable of operating the keys of a type-writer may by operating the keys of my instrument translate the letters and characters into the corresponding dots and dashes of the ordinary Morse signals.

My invention consists in the novel construction and arrangement of the train of mechanism which by the operation of the keys causes the proper opening and closing of the circuit to produce the dots and dashes representing the particular key struck.

My invention also consists in the construction and arrangement of the parts whereby my transmitter mechanism may be applied to an ordinary type-writer, whereby at the same time a Morse signal-message may be sent and an exact duplicate of it in type-printed letters be made at one operation, the parts being so adjustably connected as to permit the transmitter to be used without printing on the type-writer or the type-writer used without the transmitter, or both used together.

My invention also consists in the novel construction and arrangement of the circuit-breaking disks forming the Morse signals and in means for repeating on the same disk a short Morse character without involving a complete rotation of the disk.

My invention also further consists in other details and combinations of parts, as herein-after fully described with reference to the drawings, in which—

Figure 1 is a partial plan view of my transmitter. Fig. 2 is a vertical section taken transversely to the commutation-cylinder. Fig. 2^a is a similar section showing a different position of a commutation-disk. Fig. 3 is a section similar to Fig. 2, but showing a form of commutation-disk that stops at every half-revolution. Fig. 4 is a vertical sectional view showing the relation of my trans-

mitter to the ordinary parts of a type-writer. Fig. 5 shows means for coupling the transmitter to the type-writer. Fig. 6 is a vertical section on line 6 6 of Fig. 1, and Fig. 7 is a perspective detail of one of the disks.

In the drawings, Figs. 1 and 2, P represents the keys of a keyboard, like that of an ordinary type-writer, which keys are mounted upon the ends of levers A, pivoted at their rear ends at N and normally held up by springs C, Figs. 2, 3, and 4. These levers at an intermediate point pass beneath a composite commutation-cylinder X, formed of a series of independently-rotatable disks arranged side by side with suitable insulating-blocks inlaid on their peripheries to correspond to the breaks in the circuit forming the Morse signals, each disk representing a separate letter or character. Between each disk and its subjacent key-lever are arranged devices for making and breaking electrical contact and for starting and stopping the movement of each disk, which will be more fully described hereinafter.

The commutation-cylinder X has within its disks a continuously-rotating shaft S, Fig. 6, which is longitudinally fluted, as seen at k, to form throughout its length continuously-extended teeth. This shaft at one end is provided with a rigidly-attached gear-wheel S', (see Figs. 1 and 6,) which is in mesh with a small pinion s on the shaft of the revolving armature of an electric motor Y. To this motor the electric current is supplied to operate it through the conductor-wires y and y'. Although I have shown a small electric motor to give continuous rotation to the commutator-shaft, I would have it understood that any other motor mechanism, such as a spring or weight, may be employed, and in connection with the motor mechanism a speed-regulating governor, such as is used on the phonograph, should be employed. This I have not shown, as it is well known and forms no part of my invention.

I will now describe the means for transmitting a Morse character by the operation of the keys, reference being had to Figs. 1 and 2. Each key-lever representing a letter, a figure, or other character has its key so plainly marked as to be quickly identified, like the keys of a type-writer, and each disk has upon its periphery a succession of con-

ductive and non-conductive spaces representing a translation of that letter or character into the corresponding character of the Morse signals. The disk itself is made of metal, as seen at R, Fig. 7, and the non-conducting faces F are of hard rubber inlaid upon the peripheral surface and succeeding each other to form the dots and dashes of the Morse character. Each disk is on one side recessed out centrally about its hub portion, (see Figs. 2 and 7,) and the recess on one side extends out to and opens through the periphery of the disk. In this recess is pivoted at t a dog T, having at its inner end a tooth k', which by means of a spring V is forced, when unrestrained, into engagement with the teeth k of the central shaft S. The spring V is coiled about the shaft in the central recess, and one end is attached to the disk and the other end to the dog. The outer end Q of the dog is extended sidewise to form a foot that practically closes the lateral opening in the periphery of the disk and forms a sort of elbow-lever, so that if it be pressed inwardly it deflects the dog and throws the tooth k' of the dog out of engagement with the shaft. This disengaged position of any dog within its disk (shown in Fig. 2^a) is the normal position of all the disks except the one disk which is being operated to send its character.

The telegraph-line is extended to my instrument by means of a duplex cable and plug, the two ends of which cable (shown at Z Z') connect as follows: The positive wire Z connects with a brush or spring r, resting upon the shaft, which latter is in electrical connection with the metal of each one of the disks. The negative wire Z' (see Fig. 2) is connected to an insulated metal cross-bar B, which carries a separate roller-contact b for each disk. I prefer a roller, as it reduces friction; but a flat spring-contact might be used. The insulated bar B rests upon a stationary cross-bar G, extending from side to side of the machine immediately below the commutation-cylinder. This bar is perforated with a row of holes and through each hole below a disk there slides a short vertical pin E, bearing on its upper end a stop-roller d, whose function is to limit the rotation of the disk and cause it to always start and stop at the same point. This roller is pressed upwardly by a spiral spring e, wound about the pin E above the bar G. The pin has at its lower end a loose slip connection with the key-lever, consisting of a link L and a headed stem W, whose lower end is connected to the key-lever and whose upper end passes into the link and has a head within the link, so that when the key-lever is depressed it will pull down the link L and pin E with its stop-roller d, but allows the lever to rise immediately by the head of the stem W slipping up in the link, as in Fig. 2.

65 The contact-roller b is the full width of the

disk and always rides on the peripheral edge of the disk even when passing over the recessed opening; but the stop-roller d is of less width, as seen in Figs. 6 and 7, and is capable of dropping into said recessed opening 70 on the face of the disk and of striking against and deflecting the dog T and throwing its tooth k' out of engagement with the teeth of the shaft S. This is the normal position of rest, as seen in Fig. 2^a and is the position of 75 all the parts except those connecting the key-lever which has been depressed. When any such key-lever is depressed, its stop-roller d is drawn down away from the dog T, and the latter by the tension of the spring V will 80 instantly engage the shaft and lock the disk to the shaft, as seen in Fig. 2, with the result that this disk will rotate with the shaft and, through contact-roller b traveling on the edge of the disk, will make and break the circuit the requisite number of times and with proper intervals to transmit a Morse character corresponding to the key depressed. When the disk has made a complete revolution, the outer end of its dog again comes 85 over the stop-roller d and the spring e below it forces the roller upwardly, deflecting the dog and disengaging it from the shaft and stopping the disk exactly at the right point to start another similar character when the 90 same key is depressed.

For the shorter Morse characters it is not necessary to wait for the complete revolution of the disk to form a single character; but in such case I form two or more characters of the same kind on the same disk, the one following the other, and limit the rotation of the disk to a part of a revolution. In Fig. 3 I show two similar characters on the same disk and means for starting and stopping the 100 disk at every half-revolution. In this case there are but a single dog T and spring V; but the disk is recessed at its periphery at two diametrically opposite points. A yoke H extends around one side of the disk. Its 105 lower end is slotted to form the link L', corresponding to link L of Fig. 2. A cross-bar I, Figs. 1 and 3, extends parallel to and above the commutation-cylinder, and on it are hung short levers a, one above and in the plane of 110 each double-character disk. One end of the lever is jointed to its yoke H, and the other end has a stop-roller a' at an exactly opposite point to the stop-roller d. Now when the key-lever of this disk is depressed, stop-roller d is withdrawn from the dog, and the latter engages the shaft to turn the disk. At the same moment, however, that the lever A descends to pull stop-roller d away from 115 the disk the yoke H is pulled down, as in dotted lines in Fig. 3. This tilts lever a on fulcrum-rod I and lifts the stop-roller a' out of the upper notch in the disk and allows it to ride on the periphery of the disk. When, 120 however, the disk has turned a half-revolu- 125

130

tion, then the dog comes under the upper stop-roller a' and the latter drops into the notch, and, deflecting the dog, disengages its disk from the actuating-shaft. The next 5 time this same key is struck the upper stop-roller a' rises from the dog, again coupling the shaft and disk, and the lower stop-roller d simply moves out of the duplicate notch in the disk and allows the disk to turn. In this 10 way it will be seen the two stop-rollers d and a' move simultaneously, but have an alternate action upon the dog, thus starting and stopping the disk every half-revolution.

I will now describe the application of my 15 transmitter to an ordinary type-writer, reference being had to Fig. 4. P' is one of the keys, A' its type-lever, and B' the basket of type-hammers of an ordinary type-writer. At a point just in rear of the type-basket I 20 apply my commutation-cylinder or translating device, which is of the same construction as that already described in Figs. 1 and 2, the only change required being in the coupling and uncoupling mechanism for permitting the independent use of the type-writer, the independent use of the transmitter, or the conjoint use of the two simultaneously. For this purpose the pull-stems W have a 25 detachable connection with the key-levers, consisting each of a short bar l , pivoted to the key-lever at its lower end, so as to swing backward and forward in the plane of the key-lever and having a hook-lug l' at its upper end, which may be thrown forward to 30 hook over a corresponding hook-lug l'' on the lower end of the pull-stem W . When so engaged, it will be seen that when the key-lever is depressed it pulls down the stop-roller d and starts the translating-cylinder. If, however, the bar l be thrown toward the operator, as indicated in dotted lines, this separates the hook-lug l' from lug l'' , and the type-writer alone is operated. When the lugs l' l'' are engaged, it will be seen that the 35 operation of the keys will at the same time print a type-written message and transmit that message in the Morse characters to its remote destination, thus giving the operator and his company an absolute confirmation of the correctness of the message transmitted 40 and a permanent record thereof. If it is desired to operate the transmitter alone without the type-writer, all that it is necessary to do is to slide a subjacent stop-bar O , Fig. 4, to a 45 position close enough to the lower sides of the key-levers A' , as in dotted lines, so as to limit the extent of the depression of the key to just such slight range of movement as will unlock the translating-disks without striking 50 a blow with the type-hammers, or, if desired, the space-bar of the type-writer may be locked down and the type-hammers thrown out of printing action in any desired way. To simultaneously couple all the bars l with 55 the pull-rods W , (see Figs. 4, 5, 6,) the bars l

are all formed with a longitudinal slot u , through which passes a rod q . The ends of this rod q are connected to the opposite arms of a bail v , and this bail at a point in front of the basket of key-hammers is pushed forward or drawn backward and locked against a stop w to hold all the bars l either in the connected or disconnected position. The slots in the bars l are necessary to allow any bar l to pass down over the rod q in response 70 to the depression of its key-lever. 75

By means of my invention as thus described it will be seen that any novice or person unfamiliar with the Morse signals may telegraph these characters and retain 80 evidence of the correctness of the telegram.

I do not claim, broadly, the application of a keyboard with a bank of keys to a rotary translating device for telegraphic transmission, as I am aware that this is not new. 85

I claim—

1. A telegraphic transmitter, comprising a continuously-rotating shaft having its surface formed by longitudinal flutings into continuous longitudinal teeth along its length, 90 commutating-disks axially hung upon said shaft and recessed centrally and clutch devices for coupling the shaft to the disks arranged in the central recess of the disks.

2. A telegraphic transmitter comprising a 95 continuously-rotating shaft having its surface formed by longitudinal flutings into continuous longitudinal teeth along its length, commutating-disks hung upon said shaft and recessed centrally and also out to 100 the periphery on one side and clutch devices for coupling the shaft to the disks, said clutch devices being housed within the plane of the disk in the recess and having one end extending out to the periphery of the disk. 105

3. A telegraphic transmitter, comprising a continuously-rotating shaft longitudinally fluted to form continuous teeth along its length, a series of commutating-disks axially hung thereon side by side and formed 110 with recesses on the side, a locking-dog pivoted within the recess of each disk and having one end constructed to engage the teeth of the shaft, a spring surrounding the shaft for throwing the dog into such engagement, a 115 movable unlocking device for the dog, a key-lever operating thereupon, and an electrical contact for each disk.

4. A telegraphic transmitter, comprising a continuously-rotating shaft formed with teeth 120 throughout its length, a series of commutating-disks arranged thereon side by side, said disks being recessed centrally and out on one side to the periphery, a locking-dog arranged in this recess and having a spring to throw it 125 into engagement with the teeth of the shaft, an electrical spring-contact riding on the edge of the disk, an unlocking device for the dog made thin enough to enter the recessed opening to serve both to unlock the dog and 130

to act as a stop to limit the rotation of the disk, and a key-lever for each disk connected to and operating the unlocking device.

5. A telegraphic transmitter, comprising a continuously-rotating shaft formed with teeth throughout its length, a series of commutating-disks arranged thereon side by side, said disks being recessed centrally and out on one side to the periphery, a locking-dog pivoted in this recess and having its outer end extended across the recessed opening, a coil-spring wound about the shaft within the recess and connected at one end to the disk and at the other end to the dog, a key-lever for each disk and means operated thereby to normally hold the dog in an unlocked position.

6. In a telegraphic transmitter, a commutating-disk recessed centrally and along one side out to the periphery and a clutch device pivoted within said recess and lying within the plane of the disk.

7. A telegraphic transmitter comprising a continuously-rotating shaft, commutating-disks with clutch devices arranged therein and normally disconnected from the shaft, a key-lever for each disk having a clutch-operating device bearing peripherally against each disk and arranged immediately below the same and a slip connection between the key-lever and the clutch-operating device, whereby the key may immediately return after the downward movement without affecting the clutch-operating device.

8. A telegraphic transmitter, comprising a continuously-rotating shaft, commutating-disks arranged thereon and having each a locking device within it for connecting it with the shaft and two opposite recesses in the periphery of the disk, a double-stop device arranged, one upon one side of the disk and the other upon the opposite side to simultaneously enter and leave the two recesses and to alternately act upon the locking device therein and a key-lever operating the double-stop device.

9. A telegraphic transmitter, comprising a continuously-rotating shaft, commutating-disks arranged thereon and having each a locking device within it for connecting it with the shaft and two opposite recesses in the periphery of the disk, two opposite stop devices, a yoke H, with lever a carrying one of the stop devices, and a key-lever connected to said yoke and also carrying the other stop device.

10. The combination with the key-levers in a type-writer; of a telegraphic transmitter consisting of a series of translating-disks with means for setting any one of them into rotation, said disks being individually arranged above the corresponding type-writer key-levers, a vertical-pull device arranged centrally beneath each disk for connecting each key-lever to its own disk mechanism, said pull device having upper and lower separable members immediately beneath the disks and between them and the key-levers, a horizontal cross-rod slidably connected to the lower members and a bail connected to the ends of the rod and adapted to connect or disconnect the separable members of the vertical-pull devices.

11. The combination with the key-levers, in a type-writer; of a telegraphic transmitter consisting of translating-disks with means for setting any one of them into rotation, said disks being individually arranged above the corresponding type-writer key-levers, slotted hook-stems pivoted to the key-levers and having hooks at their upper ends, corresponding hooks for each disk-operating devices, a rod passing through the slots of the hook-stems and means for projecting the latter hook-stems into engagement with the hooks above or out of engagement, for coupling or uncoupling the transmitter to the type-writer.

GEORGE MOSES GODDARD.
